UNITED STATES PATENT OFFICE.

JOHN COCHRANE, OF MALDEN, MASSACHUSETTS, ASSIGNOR TO COCHRANE MANUFACTURING COMPANY, OF DEDHAM, MASSACHUSETTS, A CORPORATION OF MASSACHUSETTS.

DESIGN FOR DECORATIVE FABRIC.

SPECIFICATION forming part of Design No. 36,939, dated May 31, 1904.

Application filed April 9, 1904. Serial No. 202,446. Term of patent 7 years.

To all whom it may concern:

Be it known that I, JOHN COCHRANE, a citizen of the United States, and a resident of Malden, county of Middlesex, State of Massachusetts, 5 have invented a new, original, and ornamental Design for a Decorative Fabric, of which the following is a specification.

The drawing shows in plan a corner of the fabric comprising the border portion and the adjacent field.

What I claim as my invention, and desire to secure by Letters Patent, is—

The ornamental design for decorative fabric, substantially as herein shown.

JOHN COCHRANE.
